US00D905782S

(12) **United States Design Patent** (10) Patent No.: **US D905,782 S**
(45) Date of Patent: **** Dec. 22, 2020**

(54) **VIDEO CAMERA**(71) Applicant: **Google LLC**, Mountain View, CA (US)(72) Inventors: **Gregory R. Duffy**, San Francisco, CA (US); **Melissa D McLean**, Novato, CA (US); **Aamir S. Virani**, San Francisco, CA (US)(73) Assignee: **Google LLC**, Mountain View, CA (US)(***) Term: **15 Years**(21) Appl. No.: **29/740,737**(22) Filed: **Jul. 7, 2020**

CLAIM

The ornamental design for a video camera, as shown and described.

DESCRIPTION

FIG. 1 is a front perspective view of a video camera showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the video camera in which the design is embodied that form no part of the claimed design.
